FUSE SWITCH

Arthur G. Miller, Kansas City, Mo.

Application February 23, 1932, Serial No. 594,475

8 Claims. (Cl. 200—117)

This invention relates to fuse switches and more particularly to those adapted for use in high tension electric circuits wherein the fuse melts to open the circuit in case of an overload, 5 and has for its principal object to effect positive withdrawal of the fuse conductor element when the overload occurs, thereby preventing arcing of the high tension current between the fused portions of the conductor.

10 Another important object of the invention is to provide a visible signal which indicates that the circuit has been opened.

In accomplishing these and other objects of the invention, I have provided improved details 15 of structure, the preferred form of which is illustrated in the accompanying drawing, wherein:

Fig. 1 is a perspective view of a fuse switch constructed in accordance with my invention, and illustrating the fused portion of the conductor 20 withdrawn from the cartridge.

Fig. 2 is a longitudinal vertical sectional view through the switch cartridge illustrating the fusible element in functional position.

Fig. 3 is a detail end elevational view of the 25 lower end of the fuse cartridge, particularly illustrating the spring for effecting withdrawal of the fuse element from the cartridge.

Fig. 4 is a horizontal sectional view on the line 4—4, Fig. 2.

30 Referring more in detail to the drawing:—

1 designates an insulator adapted for support by a suitable bracket 2 that clamps the intermediate portion of the insulator. The opposite ends of the insulator are provided with electric 35 terminal clamps 3 and 4 to which one of the high tension circuit wires is connected.

The lower terminal 3 includes a depending fork-shaped bracket 5 having spaced hook-shaped ends 6 forming arcuate seats 7 to hingely support the lower end of the cartridge, later described.

40 The upper terminal 4 is provided with a forwardly extending yoke 8 having a latch-engaging notch 9 to receive a latch member on the upper end of the switch cartridge now described.

The cartridge includes an inner tube 10 constructed of bakelite or similar material, having a threaded upper end 11 for mounting a metallic 50 head member 12 adapted to engage in the yoke 8. The tube is of sufficient length to extend substantially below the insulator, and sleeved on its lower end is a metallic foot member 13 which is adapted to be secured to the tube by 55 a set screw 14 threadedly mounted in the foot

member and engaging against the side of the tube, as illustrated in Fig. 2.

Sleeved on the tube 10 and supported between the head 12 and the foot member 13 is an outer porcelain sleeve 15 to reinforce and protect the inner sleeve from exposure to the elements.

The foot member 13 is provided with oppositely directed pins 16 and 17 for seating in the hook-shaped ends of the bracket member 5, whereby an electric connection is made from the bracket 65 to the foot member, and whereby the cartridge is pivotally mounted. The head 12 is provided at its upper end with a threaded neck 18 having an upwardly extending lug 19 for connecting the upper end of a fuse element later described. The 70 open upper end of the head member is closed by a suitable cap 20 threaded on the neck 18 to prevent moisture from entering the upper portion of the tube.

Extending laterally from the head member is 75 an ear 21 for pivotally mounting a latch lever 22 for engaging the notch 9 to retain the upper end of the member in electric contact with the yoke member 8. The latch is adapted to be operated by a suitable ring-shaped handle member 23 80 fixed to the pivot 24 carrying the latch.

The construction thus far described is conventional for this type of fuse switch, and specifically forms no part of the present invention.

Formed on the lower front face of the foot 85 member is a downwardly and outwardly curved arm 25 having its lower end 26 terminating adjacent the end of the inner tube 10, as is clearly illustrated in Fig. 2. The outer curved face of the arm is provided with outwardly extending flanges 90 27 and 28 adjacent its side edges to form a grooved seat 29 for a spring element 30.

The spring element 30 includes a normally flat metal spring having sufficient width to be received between the flanges 27 and 28 and has its 95 upper end attached by a screw 31 in the upper end of the groove 29, while its body portion is curved about the arm and its lower end terminates in a curve 32 extending toward the axis of the tube 10.

Located on the foot member 13 directly above the arm 25 is a shoulder portion 33 for mounting a terminal screw 34 that is threadedly engaged in a recess 35 formed in the foot member.

The fuse element includes upper and lower 105 flexible conductor sections 36 and 37 connected together by a fusible connector 39 housed within the upper end of the tube 10, as illustrated in Fig. 2. The upper end of the upper conductor section is secured to the lug 19 by a screw 40 and 110

the lower end of the conductor 37 is threaded downwardly through the tube and over the spring member 30 for attachment to the screw 34 previously described, as illustrated in Fig. 2. The 5 lower section of the conductor element thus tensions the spring member over the arm when the fuse element is in functional position in the cartridge, so that when an overload occurs in the circuit and the fuse 39 melts, the tension of the 10 spring will effect withdrawal of the lower section of the conductor from the tube 10, as illustrated in Fig. 1, thereby preventing arcing and burning within the cartridge.

To assemble a fuse element in a cartridge constructed as described, the conductor sections are threaded through the tube and the upper section is secured to the lug 19 by the screw 40, and the lower end of the conductor section 37 is drawn about the curved end of the spring and over the 20 top thereof to be secured in position by the screw 34. The foot portion of the cartridge is then applied to the terminal 3 with the pins 16 and 17 thereof seated in the seats 7 formed on the lower ends of the fork member 5. The head portion of 25 the cartridge is then swung into position to engage the yoke 8, at which time the latch 22 engages the notch 9 to secure the cartridge in functional position.

The current then flows through the terminal 30 4, yoke 8, the head member 12, lug 19, conductor section 36, fuse 39, conductor section 37, terminal screw 34, and through the foot member 13 to the fork-shaped bracket on the lower terminal 3, thereby completing circuit of the conductor 35 and connecting the terminals 3 and 4.

In the case of an overload of the circuit, the excessive current melts the fuse 39, which releases the spring 30 to snap the lower conductor section from the tube 10, as shown in Fig. 1. The loose 40 wavy end of the fuse and the outwardly depending spring provide indication that the circuit has been opened, so that the linemen can tell from the ground which of the fuses has opened the circuit.

45 From the foregoing it is apparent that I have provided means for positively withdrawing the fused portion of the conductor to prevent arcing of the circuit after the fuse 39 is melted.

What I claim and desire to secure by Letters 50 Patent is:

1. In a fuse switch of the character described including a tube, head and foot members on the upper and lower ends of the tube, a fusible conductor element housed within the tube and having its ends connected to said head and foot members, an arm on one of said members, and spring means tensioned over said arm and engaging said fusible conductor element for effecting withdrawal of the fuse element from the tube 55 upon fusing thereof.

2. In a fuse switch of the character described including a tube, head and foot members on the upper and lower ends of the tube, a fusible conductor element housed within the tube and having its ends connected to said head and foot members, an arm on one of the members, and a spring strip having one end fixed to the arm and its other end extended over the arm and engaged 60 with said conductor element for effecting with-

drawal of the fuse element from the tube upon fusing thereof.

3. In a fuse switch of the character described including a tube, head and foot members on the upper and lower ends of the tube, a fusible conductor element housed within the tube and having its ends connected to said head and foot members, an arcuate-shaped arm on one of the members, and a spring adapted to be tensioned over the arm incidental to application of the fusible conductor for effecting withdrawal of the fuse element from the tube upon fusing thereof. 80

4. In a fuse switch of the character described including a tube, head and foot members on the upper and lower ends of the tube, a fusible conductor element housed within the tube and having its ends connected to said head and foot members, a curved arm on the foot member, and a spring associated with said arm for effecting withdrawal of the fuse element from the tube 85 upon fusing thereof.

5. In a fuse switch of the character described including a tube, head and foot members on the upper and lower ends of the tube, a fusible conductor element housed within the tube and having its ends connected to said head and foot members, a curved arm on the foot member and having a groove in its outer face, and a flat spring having one end attached to said arm and arranged to seat in said groove with its opposite 100 end terminating adjacent the lower end of said tube, whereby said conductor is drawn over the outer face of said spring to retain the spring in tensioned condition when the fusible conductor is in functional position. 105

6. In a fuse switch of the character described including a tube, a fusible conductor element housed within the tube, a curved spring-supporting member associated with said tube, and a leaf spring bendable over said supporting member 110 and engaging the fusible conductor element for effecting withdrawal of the fuse element therefrom upon fusing thereof.

7. In a fuse switch of the character described including a tube, head and foot members on the upper and lower ends of the tube, a fusible conductor element housed within the tube and having its ends connected to said head and foot members, a curved arm on the foot member, and a flat spring having one end attached to said 120 arm and arranged to be extended over the curved portion of the arm with its opposite end terminating adjacent the lower end of said tube, whereby said conductor is drawn over the outer face of said spring to retain the spring in tensioned condition for effecting withdrawal of said fuse element upon fusing thereof. 125

8. In a fuse switch of the character described, a tube, a fusible conductor element having the major portion thereof housed within the tube, 130 means for connecting one end of the fuse element exteriorly of the tube, means for connecting the opposite end of the fuse element within the tube, an arm member underlying the fuse element exteriorly of the tube, means for mounting the 135 arm on the tube, and a spring cooperating with the arm member to effect withdrawal of the fuse element from the tube upon fusing thereof.
